WRITING INSTRUMENT

Everis D. Munson, St. Paul, Minn., assignor to Brown & Bigelow, St. Paul, Minn., a corporation of Minnesota

Application August 13, 1953, Serial No. 373,993

1 Claim. (Cl. 120—42.03)

My invention relates to an improvement in writing instruments, and more particularly to a type wherein the ball point writing tip may be projected from the casing by pressing a knob-like member extending from the rear of the casing which causes the writing tip to be projected out of the writing end of the instrument. A spring catch positioned within the casing engages the shoulder to hold the writing tip of the ball point pen projecting from the barrel in writing position.

It is a feature to provide a ball point pen or writing instrument with means for releasing the spring catch within the casing of the pen, whereupon a coil spring within the casing automatically withdraws the writing tip of the pen back into the barrel where it is protected and the writing pen of the barrel of the pen acts as a sheath to cover the writing ball of the pen.

This writing instrument is particularly directed to the ball point type where a small steel ball is mounted in a reduced tubular end of the ink reservoir. The ink reservoir may be made of metal or plastic, such as polyethylene. When the ink reservoir is made of flexible polyethylene plastic material or vinyl plastic or a similar material, this material may be transparent or translucent and thus provides means so that the ink is visible in the reservoir tube. Where the plastic reservoir tube is transparent or translucent the user of the pen can check from time to time to determine just how much ink is left in the reservoir.

A feature of this writing instrument resides in providing a frictional means for engagement of the rear end of the plastic reservoir tube, which holds the ink reservoir tube within the operating mechanism, which moves the tube forward and backward in the casing in the operation of exposing the writing tip and in concealing the same in the barrel of the instrument.

It is a feature to confine the spring catch for holding the ink reservoir in writing position and the spring means for forcing the ink reservoir into a backward position within the rear end of the writing instrument.

It is a further feature to provide a writing instrument wherein the front end of the barrel can be removed from the rear portion so that a new ink reservoir can be placed in the writing instrument when the old one has been removed and discarded. In this construction the operating mechanism, including the coil spring for returning the writing tip into the barrel to conceal the same, together with the spring release or catch which holds the writing tip and the ink reservoir in writing position, are all confined in the rear portion of the writing instrument so that when the writing instrument is taken apart to remove an old ink reservoir and add a new one, none of the working parts of the pen are exposed or can become disassembled. The rear knob, however, projects from the rear end of the casing of the writing instrument and is exposed so that it can be depressed when it is desired to project the writing point of the ink reservoir into writing position.

The operating mechanism in the rear of the writing in-

2

strument which holds the writing ball in writing position includes a spring catch having a band-like collar which extends around the tubular portion of the operating means which frictionally holds the rear end of the ink reservoir. When this tubular end is pushed in by the knob projecting out of the rear of the casing, the band-like spring catch will move into position to engage a shoulder on the same, holding the ink reservoir in writing position while desired for writing. The pocket clip, which normally holds the pen in one's pocket, is mounted on the casing of the instrument with a spring for normally holding the pocket engaging end of the clip in operative position. The rear end of the clip projects into the path of the collar-like spring catch; thus, when it is desired to release the collar spring catch in the writing instrument, it is only necessary to press the rear end of the pocket clip inwardly, whereupon the collar-like spring catch is moved off of the shoulder of the tubular member which holds the ink reservoir and by means of a coil spring, the ink reservoir, with the tubular supporting member and the operating knob, are projected into a backward position automatically by the coil spring.

In the drawings forming part of the specification:

Figure 1 is an enlarged longitudinal section of my writing instrument.

Figure 2 is a section of the upper rear end of the writing instrument with the operating knob pressed inwardly and held by the spring collar catch.

Figure 3 is a perspective view of the collar spring catch removed from the barrel of the writing instrument.

Figure 4 is a perspective view of the tubular member which engages the rear of the ink reservoir to frictionally support the same and also the integrally-formed knob on the rear end thereof.

Figure 5 is a section on the line 5—5 of Figure 1 in the direction of the arrows.

The writing instrument A is illustrated in the drawings with a rear casing portion 10 and a front removable portion 11.

The ink reservoir B, which is normally concealed within the casing portions 10 and 11, is preferably formed of flexible plastic, such as Vinylite, polyethylene or a similar material formed of tubing and adapted to be filled with ink for use with a ball point pen. The ink reservoir B is adapted to support a restricted tubular end 12 in which is mounted a ball 13. The ball 13 may be of steel or any other suitable material wherein a true spherical ball is provided and mounted in the front end of the tube 12 so that it will freely rotate and act as an ink carrier.

The tube 12, carrying the ball 13, may be mounted in the forward end of the ink reservoir B in any suitable manner, such as supporting the tube 12 frictionally within the forward end of the plastic tube B, threading it in the same or otherwise sealing the tube 12 to the ink reservoir tube B. The tube 12 normally is made of brass or similar material and has formed therein a suitable socket for the ball 13.

The ink reservoir B is in the form of a long tube and when formed of translucent or transparent plastic material, the tube is flexible and as the ink is used up from the same by the writing ball 13, the operator may readily observe just how much ink remains within the reservoir. This is important because it keeps the operator of the instrument A fully informed at any time that the writer chooses to inform himself of how much ink remains therein. The ink reservoir tube B, with its writing end 12, form a unit which may be removed and replaced with a new unit whenever desired.

When the operator places the ink reservoir B within the pen A, the rear end of the reservoir B is adapted to be inserted in the plastic tubular member 14 which is

formed with an ink-reservoir receiving chamber 15, the inner end 15' of which is reduced in diameter to frictionally engage the inner end of the ink reservoir tube B.

The tubular plastic member 16 is positioned within the metal rear end 17 of the casing of the writing instrument A and is fixed therein with a projecting threaded end 18 which engages with the front plastic tubular end 11 of the casing of the instrument A.

A spring-operated pocket clip C is supported by the spring member 19 and is formed with an inwardly pressable end 20. Thus, the pocket clip C is supported with the pocket-engaging end 21 bearing against the side wall of the barrel of the pen A and with the free end 20 inwardly pressable, thereby providing a spring end 20 on the rear end of the clip and the spring-urged end on the other end of the clip.

A coil spring 22 is positioned in the tubular portion 16 and is adapted to bear against the forward end 23 of the tube 14 to normally hold the tube 14 in rearward position in the pen A, as illustrated in Figure 1. The rear end of the tube 14 is formed with an integral operating knob 14' which normally projects out of the rear end portion 17 of the casing of the pen. An air slot 24 is formed in one side of the tubular member 14 and a reinforcing metal strip 25 is anchored in the tubular portion 14, the purpose of which will be hereinafter described.

I provide a collar spring catch 26, illustrated, removed from the writing instrument in Figure 3, which is formed with a collar catch end 27, a tongue 28 and a spring shank arm 29. The spring arm 29 is formed with an inturned end which engages under a shoulder formed in the tube 16, to anchor the spring arm 29 in place, extending between the tubular portion 16 and the outer metal casing 17.

In operation, the writing ball 13 and the tubular end 12 of the reservoir B are projected out of the writing end of the tubular member 11 by pressing on the knob 14' at the rear of the instrument A. This operation causes the tongue 28 to engage on the shoulder 31 when the knob 14' is depressed, so that the spring collar catch 26 will hold the reservoir B in writing position with the writing ball 13 projecting out of the casing of the instrument. Figure 2 shows the knob 14' depressed and the spring collar catch 26 engaging the shoulder 31. In this position the coil spring 22 is compressed.

When it is desired to move the writing ball 13 back into the casing of the instrument, to conceal the same, the free end 20 of the clip C is pressed inward against the collar 27, thereby pushing the tongue 28 off of the shoulder 31, whereupon the coil spring 22 will automatically push the collar 14 back into the position illustrated in Figure 1, thus moving the ink reservoir B, in its entirety, with the writing end 12 back into the forward end of the writing instrument 11. In this position the

writing ball is covered by the tubular forward end of the portion 11 and the ball 13 is prevented from getting ink on the user's pocket or clothes.

The collar catch 26 is of primary importance in that it provides a simple means of engaging the shoulder 31 to hold the ink reservoir in writing position and forms a means so that the free end 20 of the pocket clip can release the spring catch 26 to cause the spring 22 to automatically conceal the writing ball 13.

The simple features of my pen will be apparent from the foregoing description and the illustrations in the drawings. While the preferred form of the construction of my pen is illustrated and described, it is to be understood that changes in the detailed construction may be made within the scope of the invention as claimed.

I claim:

In a writing instrument, a rear outer casing, an inner ink cartridge supporting tube slidably within said outer casing open at the front end thereof and having an air slot formed therein near the rear thereof, an operating knob integral with said supporting tube at the rear thereof, a shoulder formed on said supporting tube intermediate said operating knob and the open front end of said tube, a tubular bushing frontwardly of said supporting tube within and fixedly attached to said rear outer casing, said bushing having an elongated circular aperture formed in the front end thereof and an enlarged bore formed at the rear thereof, a threaded end portion formed on said bushing extending through the front of said rear outer casing, spring means contained within said enlarged bore of said bushing and abutting the lower end of said supporting tube slidably urging said tube generally in an outwardly position, a spring arm positioned within said outer casing having a continuous collar catch formed on the rear end thereof, an inturned tongue integral with said spring arm at the rear thereof and engageable with said shoulder on said ink cartridge supporting tube to hold said supporting tube in an inwardly position, a spring clip pivotally attached to said rear outer casing and having a depressible rear end engageable with said collar catch on said spring arm to release said tongue from said ink cartridge supporting tube when said clip is depressed, a hollow front casing threadably engageable with said bushing member having an aperture formed therein in the front thereof, and a flexible ink reservoir having a writing tip attached thereto at the front thereof and frictionally engageable within said ink cartridge supporting tube at the rear thereof.
